BERT H. HAWKINS, OF ROYAL OAK, MICHIGAN, ASSIGNOR TO MCCORD RADIATOR & MFG. CO., OF DETROIT, MICHIGAN, A CORPORATION OF MAINE

BUSHING ATTACHMENT FOR VALVE GRINDING

Application filed August 15, 1930. Serial No. 475,462.

This invention relates to a device in the nature of an attachment whereby the split bushing which normally serves as a guide for the stem of the valve in the engine of the present Ford Model "A" car may be employed to hold and guide the valve when grinding it to its seat.

The device of my invention is in the form of a U-shape metal clip so constructed and designed to be snapped over the split bushing adjacent the end which is uppermost when the bushing is inverted for valve grinding, so as to hold the separable parts of the bushing together, not only during the grinding operation, but also when the valve is removed from time to time to note the progress of the grinding. The device is simple in construction and inexpensive to make, and when snapped over the split bushing, effectively holds the parts together, so that they will remain on the valve stem when removing the valve from and replacing it back into the block.

The device of my invention is so constructed and designed that it will engage the split bushing in the region of the lateral flanges on the separable parts of the bushing, and serve as a seat or support for the bushing, when the latter is used as a holder for the valve during the grinding operation.

The device of my invention is also so constructed and designed as to have a snug fit about that portion of the bushing which is machined, namely, the portion which fits in the bore of the block in the normal position of the bushing as a valve guide. To carry out this feature of my invention, I so make the clip that the distance between its ends at the entrance of the U is slightly less than the outside diameter of the bushing where the clip snugly engages the same. This I accomplish by forming the curvature of the clip at this portion of a length slightly greater than half the circumference of the outside of the bushing where the clip engages the same, so that the entrance end of the clip is slightly less in the width than the outside diameter of the bushing. The result is that when the clip is applied to the bushing, the entrance end is caused to be spread apart to pass over the full diameter of the bushing, and when the clip

is completely on the bushing, the entrance end of the clip will engage the bushing for more than half its circumference, and thus effectively hold the clip on the bushing.

In the accompanying drawing:—

Fig. 1 shows the valve conditioned for grinding with the clip of my invention on the inverted bushing;

Fig. 2 is a top plan view of the clip and the bushing;

Fig. 3 is a horizontal section taken on line 3—3 of Fig. 1;

Fig. 4 is a similar view showing the clip being applied to the bushing; and

Fig. 5 is a perspective view of the clip.

In the drawing, 1 indicates the over-hang on the valve side of a cylinder block of an L-head motor, such as is employed in the present Model "A" Ford car. 2 indicates a vertical hole or bore in the over-hang below the gas chamber 3, which is formed in the over-hang below the seat 4 of the valve 5 which is of the poppet type as employed in motors of this kind.

The chamber 3 communicates with the intake or exhaust passage of the cylinder block, depending on whether the valve is an intake valve or an exhaust valve. The stem 6 of the valve extends downward through the bore 2 and terminates short of the bearing 7 for the push rod 8 which is actuated by the associated cam on the cam shaft (not shown) for lifting the valve from its seat in the operation of the motor.

The stem 6 is slidably and rotatably fitted in a guide bushing 9, which in the normal use of the valve in the engine is positioned in the bore 2 with its laterally projecting flanges 10 on the under side of the over-hang and held against the shoulder 11 by the coil spring which, through a cross-pin adjacent the lower end of the stem, closes the valve on its seat. The bushing serves to hold the valve central with respect to its seat, and also to guide the valve in its upward and downward movement.

When conditioning the valve for grinding, the spring and the cross-pin, as well as the bushing 9, are removed. This is facilitated by having the bushing made in two longitudi-

dinal separable half sections, as clearly shown in Fig. 2. By the use of the device of my invention in conjunction with this bushing, the latter may be used to hold and centralize the valve while grinding it to its seat.

My improved device is in the form of a U-shape clip, made from sheet metal. It is designed to fit over the outer side of the bushing, in the region of the flanges 10, and has a grooved or channel section 12 to accommodate or receive these flanges. The portion 13 of the clip is made to snugly engage the portion of the bushing immediately below the flanges. This portion 13 is accurately made, so as to conform to the curvature of the portion of the bushing below the flanges, which is machined to properly fit in the bore 2. In making the portion 13, it is given a circumferential length, slightly greater than half the circumference of the outer side of the bushing, as shown in Fig. 3. This makes the width of the clip at its entrance end slightly less than the diameter 25 of the bushing.

In Fig. 3, the dotted line *a* indicates the outside diameter of the bushing. A similar line *b* represents a chord of this circle on the outer side of the line *a* and about one-thirty-second of an inch distant, and parallel to line *a*. The entrance end of the portion 13 conforms in length to the length of this chord. Consequently when the clip is forced onto the bushing, this entrance end 30 will be spread apart as it passes over the full diameter of the bushing, and when the clip portion 13 comes to rest against the outside of the bushing, it will be snugly held on the bushing by reason of its entrance end extending slightly beyond half of the circumference of the bushing. The other part 14 of the clip above the channel section 12 need 35 not fit tightly about the outside of the bushing, as the holding action of the clip is confined to the portion 13 which fits about the machined part of the bushing. The portion 40 of the bushing above the flanges 10 is usually not smooth, and has a taper as indicated in Fig. 1.

Before grinding the valve, it is removed from the engine block. The two parts of the bushing are then placed about the valve stem with the bushing inverted, so as to bring its flanges uppermost. The clip is then applied to the bushing over the flanges, and holds the bushing on the stem. Then the parts are inserted back into the block. The bushing enters the bore 2, and the lower edge of the portion 13 of the clip seats against the upper 45 side of the block at the bore and the valve is thus held central for grinding as shown in Fig. 1. The valve may now be ground in the usual manner. It may be lifted from its seat from time to time, and in fact may be completely removed from the block when 50

ever necessary, without the bushing falling off of the stem due to the fact that the clip holds the two parts of the bushing together on the stem. The bushing is therefore in position to re-enter the bore 2 when the valve is put back into the block to continue or finish the grinding operation.

Attention is to be called to the fact that the clip not only holds the two parts of the bushing together on the stem when the valve is lifted from its seat and when completely removed from the block, but holds the two parts of the bushing from separating at the now lower end of the bushing, when the flared lower end 15 of the stem is drawn up adjacent the same when lifting the valve from the block. Thus the two parts of the bushing cannot be spread or wedged apart by the flared lower end of the valve stem and the bushing sections therefore are maintained in proper relation about the stem so as to re-enter the bore 2 by merely dropping the valve back to its seat, as the lower end of the bushing is not disturbed to interfere with the easy entrance of the bushing into the bore. After the valve has been ground, the bushing is removed by removing the clip, and then the bushing is inverted back to its original position, and applied in the usual manner with the spring to guide and hold the valve during the normal operation of the engine.

My device is extremely simple in structure and inexpensive to make. It is an attachment for use with the regular split bushing with which these engines are equipped, and thus enables a valve to be ground truer, because the bushing as made by the engine manufacturer is retained and used during the grinding operation, instead of depending on some other form of holder which might not have the accuracy of fit as the bushing which is supplied with the valve by the engine maker. The channel section 12 of the device not only strengthens it, but by fitting about the flanges 10 holds the device in place on the bushing. The device also lifts the two halves of the bushing out of the bore 2 when removing the valve. The side walls of the groove or channel also add to the strength of the device as a spring. Should the device wear and become loose from continued use, it can be closed slightly so that it will again fit the bushing firmly, increasing the life of the device. The edges of the device at its entrance end are flared outwardly to facilitate snapping the device on the bushing.

I claim as my invention:

1. An attachment for use with the longitudinally divided flange provided guide bushing of a poppet valve of an internal combustion engine while grinding the valve, comprising a U-shape clip to fit about the exterior of the bushing for holding its parts

together on the stem of the valve, said clip having means to accommodate the flanges on the bushing.

2. An attachment for use with the longitudinally divided flange provided guide bushing of a poppet valve of an internal combustion engine while grinding the valve, comprising a U-shape metal clip to be applied over the exterior of the bushing for holding its parts together on the stem of the valve, said clip having a channel shaped section to receive the flanges on the bushing, said clip having portions on opposite sides of said channel section with one portion fitting against the exterior of the bushing.

3. An attachment for use with a longitudinally divided flange provided guide bushing of a poppet valve of an internal combustion engine while grinding the valve, comprising a U-shape metal clip to be applied over the bushing for holding its parts together on the stem of the valve, said clip having a channel section to receive the flanges of the bushing, said clip having sections on opposite sides of the channel section, one of said sections having a curvature conforming to that of the outside of the bushing and having a circumferential length slightly more than half the circumference of the outside of the bushing.

4. An attachment for use with a longitudinally divided flange provided bushing for a poppet valve of an internal combustion engine while grinding the valve, comprising a U-shape metal clip to be applied over the outer side of the bushing for holding its parts together on the stem of the valve, said clip having a channel section to receive the flanges on the bushing, said clip having portions on opposite sides of the channel section extending part way about the bushing, the entrance end of the clip being slightly less in width than the full diameter of the outside of the bushing so that the clip in being applied to the bushing will snap over the same to hold the parts of the bushing on the stem of the valve.

5. An attachment of the character described comprising a U-shape metal clip adapted to be applied over the outside of a longitudinally divided flange provided valve guide bushing for holding its parts together on the stem of a valve, said clip having a channel shaped section intermediate its ends to receive the flanges of the bushing, the portions of the clip on opposite sides of the channel section being shaped to fit about the bushing with one portion made to conform to the curvature of that part of the bushing which fits in the bore in the cylinder block.

In testimony whereof I affix my signature.
BERT H. HAWKINS.
